UNITED STATES PATENT OFFICE.

EDNY D. BENNETT, OF MOUND CITY, KANSAS.

FOLDED-PAPER SUPPORT AND GUIDING ATTACHMENT FOR TYPEWRITERS.

Application filed March 30, 1925. Serial No. 19,430.

This invention relates to paper support and guiding attachments for typewriters, and my object is to produce a device for the support of long strips of paper, preferably 5 folded accordion-like, so that the weight of the support and the paper is entirely removed from the carriage of the typewriter as distinguished from the construction set out in my former Patent No. 1,247,071, 10 issued November 20, 1917, in which the weight of the support and paper is borne by the typewriter carriage.

Another object is to produce a support which is readily adjustable to accommodate 15 all standard typewriting machines and which is also adjustable to accommodate paper of different widths.

A still further object is to produce a paper support which is of strong, durable, efficient 20 and inexpensive construction and in order that it may be fully understood, reference is to be had to the accompanying drawing, in which:—

Figure 1 is a front elevation of a device 25 embodying the invention.

Figure 2 is a top plan view of the same.

Figure 3 is a section on the line III—III of Figure 2.

Figure 4 is a perspective view of one of 30 the paper supporting members.

Figure 5 is a perspective view of a slightly modified form of paper support.

In the said drawing, where like reference characters identify corresponding parts in 35 all of the figures, 1 indicates a suitable base which if of sufficient weight, may rest on the typewriter table or support, or if relatively of light weight, may be permanently attached thereto, said base having a post 40 extension 2 having a central bore or passage-way 3. Adapted for sliding adjustment within the bore 3 is a rod 4, held in any predetermined position of adjustment by a set screw 5. The upper end of said rod is 45 enlarged as at 6 and formed with a pair of laterally projecting ears 7.

Embracing and pivotally pinned at one end to said ears 7 by means of a pin 8, for horizontal swinging movement, is a skeleton 50 arm or supporting member 10, the opposite end of said arm 10 being pivotally secured by a pin 12 to an end of a second skeleton arm or supporting member 14. The pivotal adjustment of the arm 10 around the pin 8

is limited only by abutment of said arm 65 with the enlarged upper end 6 of the arm 4. In order to limit the pivotal movement of the arm 14 around the pin 12, in an expanding direction, the former is formed with an extension 15 which, through abutment with 80 an upstanding pin 16 on the arm 10, limits the pivotal movement of said arms 10 and 14 to a position in alinement with each other, the pivotal movement in the opposite or contracting direction being limited by 85 engagement of said pin 16 with a notch 17 cut in the arm 14, as will be apparent most clearly by reference to Figure 2.

The free end of the supporting member 14, is swivelled on a pin 18 rigidly secured 70 at its upper end to an L-shaped strap 19, rigidly secured at its ends to extremities of a pair of spaced parallel sleeves or tubes 20, permanently engaged at their opposite ends with the bottom portion of a right-angle 75 shaped paper guide and support 21. It will be noted that the upstanding portion of said support is shorter than the bottom portion (see Figures 3 and 4), and at one end said upstanding portion is formed at its front 80 end with a right-angle flange 22 overlying the bottom of the support and providing a paper feed opening or slot 23, for a purpose which will hereinafter appear.

The projecting end of the bottom portion 85 of the support 21, is hinged at 24 to a strap member 25, and hinged at 26 to the other end of the strap is a clamp 27 of such character as to be universal, that is, adapted to grip the paper guide 28 of any standard 90 typewriter platen 29 (see Figure 3).

The spaced sleeves 20 slidably receive a pair of spaced rods 30, rigidly secured at one end to a pair of depending ears 31 of a paper support and guide 32 corresponding in all respects with the L-shaped guide 21, just described. It will be evident that the guide 32 is slidable toward and from the guide 21 to accommodate paper of different widths, and said guide is equipped 100 with a hinged strap member 25, and the latter is hinged at 26 to a clamp 27, for engagement with the paper guide 28.

When the device is in use, the clamps 27 will be rigidly engaged with the plate guide 105 28 and a long strip of paper, preferably folded accordion-like (see Figure 3) is placed in the supports 21 and 32, it being

understood that the support 32 is adjusted by sliding its rods 30 in the sleeves 20 to accommodate the width of the paper strip, and the free end of the paper is fed out through the slots 23 over the straps 25 to the platen 29 of the typewriter. The typewriter is now operated in the ordinary manner, the hinges 24 and 26 accommodating any slight difference in the height of the device as regards the typewriter platen, and the pivot pins 8, 12 and 18 permitting the arms 10 and 14 to swing or oscillate back and forth in accordance with the movements of the carriage, said arms transmitting the entire weight of the supports and paper to the rod 4. It will be noted that as the platen is rotated the paper will be unfolded and withdrawn from the supports, the overlying portions of the L-shaped flanges 22 preventing the paper from kicking or buckling upwardly and the depending portions preventing the folded bulk of the paper from being dislodged forwardly off the supports.

In Figure 5, a device corresponding in all respects to that described is illustrated, except that the extension portions of the bottoms of the supports 21 and 32, are bent upwardly adjacent flat overlying flanges 33, to form the feed slot or opening. The operation of this modification is similar in all respects to the operation above-described. With this arrangement the paper is unfolded from the top instead of the bottom of the mass, and because of this there is a tendency for the paper to buckle upwardly. To obviate this a small piece of card board or other light weight may be placed upon the folded paper.

When it is desired to detach the device from the typewriter, the clamps 27 are disengaged from guide 28, and the arms 10 and 14 are pivoted around the pins 8, 12 and 18, until the lower rod of the slideable pair of rods 30, is engaged with an opening 34 formed in the upper end of the enlarged portion 6 of the rod 4. The rod 30 may be held in this position through clamping engagement by a set screw 35 threaded in the extremity of said portion 6 (see Figure 1). When the device is thus folded and locked all tendency for the parts to vibrate or swing back and forth is eliminated.

From the above description it will be apparent that I have produced a device of the character outlined which possesses all of the features of advantage set forth as desirable, and while I have described and claimed the preferred embodiment of the same, I reserve the right to make all changes

properly falling within the spirit and scope of the appended claims.

I claim:

1. In a device of the character described, the combination with a support, of an arm pivoted for horizontal movement to said support, a second arm pivoted at one end for like movement, to said first-named arm, a paper support pivoted to the other end of said second arm, and means carried by said paper support for detachable engagement with a horizontally-movable carriage.

2. In a device of the character described, the combination with a support, of an arm pivoted to said support, a second arm pivoted to said first-named arm, a paper support pivoted to the said second arm, and hinge means carried by said paper support and adapted for engagement with a movable carriage to permit of relative up and down movements of said paper support and carriage.

3. In a device of the character described, the combination with a support, of an arm pivoted to said support, a second arm pivoted to said first-named arm, a paper support member pivoted to the said second arm, a second paper support member carried by and movable toward and from said first-named paper support, and hinge arms carried by each paper support, and clamps hinged to said arms and adapted for engagement with a movable carriage to permit of relative up and down movements of said paper supports and carriage.

4. In a device of the character described, a post, a vertical rod adjustable on the post, a typewriter carriage guide, a paper support attached to and movable with said guide, and a pair of arms pivotally connected for horizontal movement, one having a pivotal connection with said vertical rod and the other a pivoted connection with and forming a support for the paper support.

5. The combination of swinging extensible and contractible support having a fixed axis at one end and free at the other end for horizontal movement in any direction, a bracket pivoted to the free end of the support, a pair of parallel sleeves carried by the bracket, a pair of rods extending slidably through the sleeves, and a paper support and guide comprising two parallel members respectively mounted rigidly on said sleeves and rods, and adapted to cooperatively support and guide paper for use on a typewriting machine.

In witness whereof I hereunto affix my signature.

EDNY D. BENNETT.
